CLAIM

The ornamental design for a multiple compartment cassette, as shown and described.

DESCRIPTION

FIG. 1 is a perspective view of the multiple compartment cassette of the present invention;

FIG. 2 is another perspective view of the multiple compartment cassette shown in FIG. 1;

FIG. 3 is a right side view of the multiple compartment cassette shown in FIG. 1;

FIG. 4 is a left side view of the multiple compartment cassette shown in FIG. 1;

FIG. 5 is a bottom view of the multiple compartment cassette shown in FIG. 1;

FIG. 6 is one end view of the multiple compartment cassette shown in FIG. 1; and,

FIG. 7 is the other end view of the multiple compartment cassette shown in FIG. 1.

The multiple compartment cassette may be used in a variety of environments, particularly in the medical arts. For example, the multiple compartment device may include at least one porous medium such as a filter, and may be used in processing fluids such as parenteral fluids, more preferably fluids to be administered intravenously.

The multiple compartment cassette comprises a housing, preferably a transparent or semi-transparent housing, and includes at least two compartments.
